UNITED STATES PATENT OFFICE.

JACOB MERSEREAU, OF PORT CHESTER, NEW YORK.

DESIGN FOR FLOWER-VASE.

Specification forming part of Design No. 6,709, dated June 17, 1873; application filed May 24, 1873.

To all whom it may concern:

Be it known that I, JACOB MERSEREAU, of Port Chester, in the county of Westchester and State of New York, have invented a new and original Design for Flower-Vase; and I do hereby declare the following to be a full, clear, and exact description thereof, which will enable those skilled in the art to make and use the same, reference being had to the accompanying drawing forming part of this specification, which drawing represents a perspective view of my vase.

My vase consists of four parts, viz., the overhanging apron, the vase proper, the column, and the foot; and each of these parts is ornamented so as to present a novel and neat appearance, while all the parts, when put together, form a vase of a highly ornamental character.

In the drawing, the letter A represents the overhanging apron, which is ornamented by convex leaves *a* and intervening roof-shaped ribs *b*. Beneath this apron is the vase B, the outer surface of which is embellished by ornaments *c*, as shown. This vase is supported by

a column, C, the shaft *d* of which is tapering and octagonal, each side of the octagon forming a panel, *e*, which is separated from the adjoining panels by ornamented corner-strips *f*. The capital *g* of this column is composed of curved members, which are formed and ornamented as shown. The column C is supported by a foot, D, the lower part of which is flaring, and ornamented by projections *h*, while its upper part is reduced in diameter, and ornamented by beads and concaves.

What I claim as new, and desire to secure by Letters Patent, is—

1. The design for the apron A, as shown and described.
2. The design for the vase B, as shown and described.
3. The design for the column C, as shown and described.
4. The design for the foot D, as shown and described.

JACOB MERSEREAU.
